UNITED STATES PATENT OFFICE.

JOHN MOST, OF JERSEY CITY, NEW JERSEY, ASSIGNOR TO WHEELER & WILSON MANUFACTURING COMPANY, OF BRIDGEPORT, CONNECTICUT, A CORPORATION OF CONNECTICUT.

PLAIT-FOLDER FOR SEWING-MACHINES.

SPECIFICATION forming part of Letters Patent No. 712,399, dated October 28, 1902.

Application filed April 3, 1902. Serial No. 101,263. (No model.)

To all whom it may concern:

Be it known that I, JOHN MOST, a citizen of the United States, residing at Jersey City, in the county of Hudson and State of New Jersey, have invented a certain new and useful Improvement in Plait-Folders for Sewing-Machines, of which the following is a full, clear, and exact description.

My invention relates to plait-folders for sewing-machines.

The object of my invention is to provide a box-plait folder which is readily adjustable for box-plaits of various widths and of extremely simple construction.

My invention comprises suitably-shaped adjustable folders or tongues upon which the material is plaited on its way to the stitching mechanism of the sewing-machine, together with suitable means for supporting said folders in proper relative position.

My invention further consists in certain details of construction and combinations of parts, all as I will now proceed to describe and claim.

In the accompanying drawings, illustrating my invention, in the several figures of which like parts are similarly designated, Figure 1 is a plan view. Fig. 2 is a front edge elevation of the same looking in the direction in which the material travels toward the stitching mechanism of the sewing-machine. Fig. 3 is a cross-section taken in the plane of line xx , Fig. 1. Fig. 4 is a plan view similar to Fig. 1, but showing the material as it passes through the folders on its way to the stitching mechanism of the sewing-machine with the folder adjusted for a box-plait to be sewed by a double line of stitches. Fig. 5 is a detail perspective view of one of the adjustable folders. Fig. 6 is a view similar to Fig. 4, but partly broken and showing the folder adjusted for a box-plait to be sewed by a single line of stitches.

1 is the base-plate, provided with screw-holes 2 and 3, through which screws (not shown) are passed to secure the device upon the bed-plate of a sewing-machine.

4 is the right-hand folder-plate and 5 is the left-hand folder-plate, both of which are adjustably secured to the base-plate 1 by screws

6 and 7, which pass, respectively, through slots 8 and 9, formed in said folder-plates, and are tapped within said base-plate. Each of the folder-plates 4 and 5 is provided on its under side, preferably at the front edge, with a rib or feather 10, adapted to fit and slide within a groove 11, made in the upper surface of the base-plate, (see Fig. 3,) which serves to keep said folder-plates in proper alignment during the operation of adjusting them for box-plaits of various widths.

12 and 13 are upwardly and rearwardly curled flanges formed on the adjacent edges of the folder-plates 4 and 5, respectively, which terminate in flat tongues 14 and 15, projecting from the delivery edge of said folder-plates, said tongues jointly forming the core or former upon which the box-plait 16 is folded.

17 is a plate supported in position directly over the folder-plates 4 and 5 by an overhanging bracket-arm 18, sufficient space being left between said plate 17 and folder-plates 4 and 5 to permit the easy passage of the material.

The overhanging bracket-arm 18 is attached at one end to the base-plate 1 by screws 19 and 20, while to the other end of said bracket-arm is secured the plate 17 by screws 21 and 22. 23 and 24 are screws tapped within the opposite ends of said bracket-arm and bearing respectively upon the plate 17 and base-plate 1, the function of which screws will be presently explained.

25 and 26 are depending folding-fingers, whose delivery ends protrude beneath the tongues 14 and 15, while the heel ends of said folding-fingers are secured to the overhanging plate 17 by screws 27 and 28, which pass through slots 29 and 30 and are tapped within said plate 17.

31 is a groove formed within the upper surface of the plate 17 similar to the groove 10 in the base-plate 1, and each of the folding-fingers 25 and 26 is provided on its under side with a rib or feather 32, adapted to fit and slide within said groove in a manner similar to the folder-plates 4 and 5 and for a like purpose.

The fabric to be plaited is passed between

the base-plate 1 and the overhanging plate 17 over the core formed by the curled flanges 12 and 13 and tongues 14 and 15 and thence under the folding-fingers 25 and 26, the ends 5 and inner edges of the latter being covered, as shown in Fig. 4, by the overlapping folds of the newly-formed plait.

The feed mechanism of the sewing-machine serves to draw the fabric through the folder 10 in any usual manner.

33 indicates a box-plait folded for and sewed by a double row of stitches, (see Fig. 4,) and 34 is a box-plait folded for and sewed by a single line of stitches. (See Fig. 6.)

15 It will be observed that in Fig. 6 the delivery ends of the folding-fingers 25 and 26 are somewhat overlapped, so as to cause the underlying folds of the box-plait to likewise overlap, thus enabling a single line of stitches 20 centrally disposed to unite simultaneously all the folds of the plait.

It is often desirable to form a series of box-plaits parallel with each other, and for this purpose I have provided an adjustable guide 25, which is secured to the plate 17 by a set-screw 36, which passes through a slot 37, formed in the body portion of said guide. The depending flanges 38 of said guide bear against the front edge of the plate 17, and 30 thereby serve to hold said guide in proper alignment.

In making a series of parallel box-plaits the guide 35 is adjusted for the distance it is desired to have the plaits apart, and after 35 having completed one box-plait the material is moved or adjusted until the guide 35 is in proper position beneath the edge of said previously-formed plait, as shown in Fig. 4, and the operation continued until the desired 40 number of box-plaits has been obtained.

By loosening the screw 19 and tightening the screw 23 the bracket-arm 18 may be slightly tilted upwardly to provide for a limited vertical adjustment of the folding-fingers 45 25 and 26, and in order to tip the said fingers toward and from the bed-plate the screws 21 22 24 may be similarly adjusted, and the free ends of the folding-fingers thus inclined more or less in the direction of their length.

50 Having thus described my invention, what I claim as new, and desire to secure by Letters Patent, is—

1. In a box-plait folder for sewing-machines, the combination of a base-plate, and right and 55 left hand folder-plates adjustably secured thereon and provided on their adjacent edges with tongues which jointly form the core around which the box-plait is made, with adjustable folding-fingers adapted to coöperate 60 with said tongues, and means for supporting said folding-fingers in proper relative position.

2. In a box-plait folder for sewing-machines, the combination of a base-plate, and right and 65 left hand folder-plates adjustably secured thereon and provided on their adjacent edges

with tongues which jointly form the core around which the box-plait is made, with an overhanging plate, adjustable folding-fingers arranged thereon and adapted to coöperate 70 with said tongues, and a bracket-arm on said base-plate by means of which said overhanging plate is supported.

3. In a box-plait folder for sewing-machines, the combination of a base-plate, right and left 75 hand folder-plates adjustably secured thereon and provided on their adjacent edges with tongues which jointly form the core around which the box-plait is made, an overhanging plate, a bracket-arm by means of which said 80 overhanging plate is supported, and adjustable folding-fingers carried by said overhanging plate and adapted to coöperate with said tongues, with an adjustable guide also carried by said overhanging plate. 85

4. In a box-plait folder for sewing-machines, the combination of a base-plate provided with a groove, and right and left hand folder-plates provided on their adjacent edges with 90 tongues which jointly form the core around which the box-plait is made, said folder-plates provided with ribs or feathers adapted to fit and slide within the groove in said base-plate, with adjustable folding-fingers adapted to coöperate with said tongues, and means for 95 supporting said folding-fingers in proper relative position.

5. In a box-plait folder for sewing-machines, the combination of a base-plate, right and 100 left hand folder-plates provided on their adjacent edges with tongues which jointly form the core around which the box-plait is made, said folder-plates being provided with ribs or feathers adapted to fit and slide within the groove in said base-plate, an overhanging 105 plate having a groove, adjustable folding-fingers carried by said overhanging plate and adapted to coöperate with said tongues, said folding-fingers being provided with ribs or feathers adapted to fit and slide within the 110 groove in said overhanging plate, whereby the proper alignment of said fingers is preserved during adjustment, and means for supporting said overhanging plate in proper position, substantially as set forth. 115

6. In a box-plait folder for sewing-machines, folder-plates, and a base-plate upon which they are mounted, said folder-plates having curled flanges terminating in flat tongues, combined with adjustable folding-fingers converging beneath the said tongues and adapted to overlap. 120

7. In a box-plait folder for sewing-machines, a base-plate, folder-plates adjustable toward and from one another upon said base-plate, 125 and having curled flanges terminating in flat tongues, folding-fingers extending beneath the tongues, and means for adjusting said fingers toward and from one another.

8. In a box-plait folder for sewing-machines, 130 a base-plate, an overhanging arm mounted thereon, means to tilt said arm vertically, a

plate supported upon said arm, and folding-fingers on said plate, combined with complementary folder-plates on the base-plate.

9. In a box-plait folder for sewing-machines, a base-plate, an overhanging arm mounted thereon, means to tilt said arm vertically, a plate supported upon said arm, folding-fingers on said plate, and means for tipping the said plate on said arm so as to incline the

fingers relatively to the base-plate, combined with complementary folder-plates on the base-plate.

In testimony whereof I have hereunto set my hand this 1st day of April, A. D. 1902.

JOHN MOST.
